BELT LOADING DEVICE FOR SUBCALIBER AMMUNITION

Chester E. Hoskins, Springfield, Mass.

Application October 17, 1945, Serial No. 622,914

14 Claims. (Cl. 86—48)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a loading device for ammunition belts and is directed more particularly to an apparatus for facilitating the loading of sub-caliber ammunition into machine gun belts.

The loading of machine gun ammunition belts has been such a slow, labor-consuming job, that to a considerable extent, the potential saving of using lower cost ammunition has been neutralized and a big labor and time element has been added.

In loading ammunition belts to fire sub-caliber ammunition, for example, a cal. .30 belt with cal. .22 ammunition, as heretofore practiced, the empty cal. .22 cartridge cases are ejected from cartridge holders by hand, fresh cal. .22 cartridges are inserted in the holders and then seated, and the loaded holders are loaded into adapters pre-assembled to the belts, a total of four operations.

Accordingly, it is an object of this invention to provide a simple and efficient means for loading sub-caliber ammunition units into standard caliber machine gun belts.

A further object of this invention is to provide a machine for assembling sub-caliber ammunition units.

A particular object of this invention is to provide a novel machine for ejecting spent caliber .22 cartridge cases from caliber .30 holders, inserting unspent cartridges, seating same and assembling the loaded holders into adapters in appropriate caliber .30 ammunition belts, ready for feeding into a machine gun.

The specific nature of the invention as well as other objects and advantages thereof will clearly appear from a description of a preferred embodiment as shown in the accompanying drawings in which:

Fig. 1 is a front elevational view of an assembled belt loading device for sub-caliber ammunition constructed in accordance with this invention.

Fig. 2 is an isometric view of the base portion of the loading device.

Fig. 3 is an enlarged scale elevational view of the cartridge holder ejection and loading elements shown with the operating member in a partially retracted position.

Fig. 4 is a view similar to Fig. 3 but showing the operating member in its forward position.

Fig. 5 is a view similar to Fig. 3 but showing

2

the operating member in its completely retracted position.

Fig. 6 is an isometric view of the cartridge tube latch.

Fig. 7 is an isometric view of the discharge chute and latch for the ejected cartridge cases.

Fig. 8 is an enlarged scale fragmentary elevational view showing the pin and slot connection between the operating member and the belt feed slide.

Fig. 9 is a sectional view taken along the plane 9—9 of Fig. 8.

Fig. 10 is an exploded view sub-caliber ammunition unit.

15 In Fig. 10 there is shown a typical sub-caliber ammunition unit comprising an adapter 72, cartridge holder 73 and sub-caliber cartridges 77.

In Fig. 1 is shown in assembled relation a belt loading device including a frame or base portion 1 having a cover plate 10, a cartridge holder feed assembly 20, an ammunition feed assembly 30, an operating slide assembly 40, and a belt feed slide assembly 60.

The frame 1 is provided with one pair of horizontal, longitudinal, aligned slots 2 and 3 for slidably engaging operating slide assembly 40, and two pairs of horizontal transverse, aligned slots, one pair 4 and 5 for guiding the ammunition belt 11, the other pair 6 and 7 for slidably engaging belt feed assembly 60.

Cover plate 10 is assembled to the frame by any conventional means such as screws 11. It is provided with a longitudinally-extending slot 12 and a special shaped opening 13, as shown in Fig. 2, said slot 12 and opening 13 being in alignment, both with one another and with slots 2 and 3 in frame 1. Also a smaller opening 14 is provided in the cover plate in alignment with slots 4 and 5 in frame 1, as shown, for a purpose which will presently appear.

The cartridge holder feed assembly 20 consists of two guide bars or uprights 21 and 22 which are channeled as at 23 and 24 to slidably receive the ends of cartridge holders 73 (Fig. 4). A conventional feed hopper (not shown) may be supplied at the top of guide bars 21 and 22 if desired. These guide bars are assembled in vertical parallelism on cover plate 10 with the open sides of the U-shaped channels 23 and 24 facing each other, defining a feed chute aligning with opening 13 in cover plate 10, said opening 13 being of such shape and size that it permits of free side-wise passage therethrough of cartridge holders 73.

It will be appreciated that channels 23 and 24 define a vertically extending chamber or space

adapted to slidably receive cartridge holders 73, which chamber is a continuation of opening 13. A plate 26 may be attached to upright bars 21 and 22 near their upper ends to hold them in spaced relation.

Horizontal coaxial holes 27 for ejecting spent cartridge cases are provided through guide bars 21 and 22, aligning with the axis of a holder 73, several holders up when holder feed assembly 20 is filled. A single horizontal loading hole 28 is provided through guide bar 22 to align with the axis of a holder somewhat below that in the cartridge case ejecting position.

A sloping chute 29 is provided on the side of guide bar 22 just below hole 27 therein and within said chute a catch 29a (Fig. 7) is provided for a purpose to be shown later.

The ammunition feed assembly 30 includes an ammunition feed tube 31 leading from a conventional cartridge feed hopper (not shown) and supported at an angle by a bracket 32, said feed tube 31 curving adjacent its lower end to terminate in a horizontal guide 33 above a loading block 34. Loading block 34 is secured adjacent guide bar 22, and is provided with a loading groove 35 in axial alignment with hole 28 in guide bar 22. A spring latch 36 associated with loading block 34 intersects a slot 37 provided in feed tube 31 adjacent guide 33 and is adapted to thereby retain the next cartridge 77 in ammunition feed tube 31 and prevent said cartridge from sliding down into guide 33, except when said spring latch 36 is pressed out of the way by engagement with a shoulder 55 on lug 50 on operating slide assembly 40, as will be described.

The operating slide assembly 40 is carried by an operating bar or loading member 41 slidably engaged in the slots 2 and 3.

The right end portion of operating bar 41 as shown in Fig. 3 is undercut as at 42 providing thereby a shoulder 43. The left end portion as shown in Fig. 3 is also undercut, as at 44, thereby providing a shoulder 45, and is overcut as at 46, providing a shoulder 47.

In overcut 46, immediately adjacent shoulder 47, is provided a trough 48 in longitudinal alignment with opening 13 in cover plate 10. Trough 48 is so spaced on operating bar 41 that when said bar is in the extreme right position, trough 48 is directly below opening 13 in position to receive a cartridge holder therethrough. The floor of overcut 46 is provided with a cam slot 49, the purpose of which will appear later.

On top of operating bar 41 there is provided a lug 50 (Figs. 3 and 5) from which a cartridge loading plunger 51 extends in axial alignment with loading block groove 35 and loading hole 28 in guide bar 22. An ejector carrier 52 is integrally secured to the side of lug 50 and this extends past guide bars 21 and 22 and terminates in a second lug 53, on which is provided a cartridge case ejector 54, in axial alignment with holes 27 through guide bars 21 and 22. Cartridge case ejector 54 is a rod-like member of such length that when operating bar 41 is at its extreme right hand position (Fig. 5) said ejector extends through holes 27 in guide bars 21 and 22 and projects beyond guide bar 22 a distance slightly greater than the length of a caliber .22 cartridge case 79 so that rim 80 of said case projects over catch 29a, which engages cartridge case 79 under said rim 80, thereby preventing reentry of said cartridge case 79 into hole 27 in guide bar 22, when ejector 54 is retracted by motion of operating bar 41, cartridge case 79 in-

stead being released into chute 29 and guided by the latter into a suitable receptacle (not shown).

The belt feed assembly 60 consists of a belt feed slide or carrier 61, which is provided with a transverse recess 62. An upstanding stud 63 is provided within said recess 62 and in assembled relation is engaged in cam slot 49 in operating bar 41, being actuated thereby and accordingly biasing belt feed slide 61 outwardly when operating bar 41 is moved to the left (Fig. 4) and inwardly when said operating bar 41 is moved to the right (Fig. 5). A belt feed pawl 65 is pivotally secured in slot 64 against the thrust of a spring 66 so as to maintain said pawl 65 in engagement with ammunition belt 71. Belt 71 is of conventional form but is pre-loaded with holder adapters 72 which receive cartridge holders 73 in inserted relation, therein.

Belt feed pawl 65 engages belt 71 between adapters 72, thereby conveying said belt inwardly the distance of one pocket or cartridge receptacle thereof for each cycle of movement. A belt holding pawl 68 is pivotally secured in belt holding pawl bracket 67, said bracket being secured on cover plate 10 above opening 14 through which said pawl 68 extends and is maintained in interference engagement with ammunition belt 71 by the thrust of a spring 69. The arrangement is such that member 68 will engage ammunition belt 71 and allow the adapters to slide thereunder when the belt 71 is feeding but will prevent reverse motion by engaging said belt 71 between adapters 72 when feed slide 61 is biased outwardly, said bracket 67 also serving as a guide for ejector carrier 52 (Figs. 3, 4, 5).

To initiate operation of the belt-loading device, the operating slide bar 41 is set at the extreme left as shown in Fig. 4, in which position shoulder 55 on lug 50 thereof is in engagement with spring latch 36 on feeder block 34, thereby holding said spring away from the line of flow of cartridges 77 in ammunition feed tube 31 so that when the tube is filled with cartridges, the bottom cartridge can pass into guide 33 and be ready to drop into groove 35 when plunger 51 is withdrawn. Feed tube 31 is now filled with fresh cartridges with the bullet down.

Next, a plurality of cartridge holders 73 with fresh cartridges therein, sufficient to include the space next below loading hole 28 are placed in the cartridge holder feed slide and then a plurality of empty holders sufficient to include the space next below ejector holes 27 are added. The holder guide is now filled with holders, either empty or containing discharged cartridges as ejected from the machine gun. Lastly, a belt 71 having adapters 72 therein is fed into slot 4 with the first adapter being pushed past belt feed pawl 65. The loader is now ready to operate.

The operating cycle is divided into two stages, the first being accomplished by moving operating bar 41 from left to right (Fig. 5) and the second by moving said bar 41 from right to left.

The first stage consists of five operations as follows:

First, ejector 54 passes longitudinally through the aligned cartridge holder 73, ejecting the spent cartridge case through hole 27 in guide bar 22.

Second, lug 50 is disengaged from spring latch 36, said spring retracting into slot 37 in ammunition feed tube 31 to prevent the cartridge next to guide 33 from entering therein.

Third, cartridge plunger 51 is withdrawn from cartridge loading hole 28 and cartridge loading

groove 35 beneath guide 33, thereby allowing the cartridge 71 therein to drop into groove 35 in position to be impelled through loading hole 28 into assembly in the aligned cartridge holder 73. Spring latch 36 now in the retracted position in slot 37 has meanwhile maintained interference with the next cartridge, keeping it from pressing against the cartridge in guide 33 so that said cartridge in guide 33 was entirely free to drop into groove 35 when cartridge plunger 51 was withdrawn.

Fourth, trough 43 is brought under and into alignment with special shaped opening 13 and the bottom loaded holder 73 drops therein, being retained in position to be impelled into the adapter 72 upon the next movement of operating bar 41.

The fifth and last part of this half of the operating cycle is the biasing inwardly of belt feed slide 61 by means of the engagement of stud 63 in cam slot 49, whereby belt feed pawl 65 through engagement with belt 71, as heretofore described impels said belt inwardly through slot 4 the distance of one adapter.

The second half of the operating cycle consists of moving operating bar 41 to the left (reverse of first half), thereby accomplishing five operations as follows:

First, ejector 54 is withdrawn from holes 27 in guide bars 21 and 22 and from the holder 73 in alignment therewith. Cartridge case 79 being in engagement with catch 29a is prevented from re-entering hole 27 and hence drops off into chute 29 for conveyance into whatever receptacle may be provided.

Second, cartridge plunger 51 moves longitudinally through groove 35 impelling the cartridge 71 lying therein through hole 28 in upright 22 into the holder 73 in alignment therewith, seating it therein.

Third, lug 59 engages spring latch 36, disengaging it from slot 37 in feed tube 31, and thereby allowing the bottom cartridge therein to move into guide 33.

Fourth, the cartridge holder 73 in trough 43 is conveyed forward and seated in the adapter 72 in alignment therewith, in belt 71.

Fifth, slide 61 is biased outwardly by the engagement of cam slot 49 and stud 63 while belt holding pawl 68 holds the ammunition belt 71 in location and belt feed-pawl 65 slips forwardly under the next adapter, coming to rest just forward of it in a position to impel the belt inwardly when operating bar 41 is again moved to the right. This completes the cycle of operation.

Operation can be by hand, in which case a handle of convenient form could be attached to one end of operating bar 41, or by a power driven member, connected by any convenient conventional means.

If hand operated, shoulders 43 and 45 on the under side of operating bar 41 will serve as stops for limiting the motion of said bar, whereas, if machine operated, these shoulders can, if desired be eliminated, since machine operation makes the presence of stops unnecessary.

It is therefore evident that this invention provides a simple and efficient means for loading sub-caliber ammunition into machine gun belts. It should be noted that portions of the machine described are capable of separate utility. For example, regular ammunition could be substituted for the cartridge holders, and, eliminating ejector 54, the machine utilized to load regular cartridges into the belt. Or the device may be

operated without the belt to eject fired cartridges and load fresh cartridges into the cartridge holders.

I claim:

1. A machine for loading subcaliber ammunition in a belt comprising a reciprocable loading member, a feed chute adapted to receive a row of hollow cartridge holders, said feed chute having a discharging end disposed adjacent the path of said loading member whereby the foremost cartridge holder in said chute is positioned in the path of forward movement of said loading member, means for successively positioning a fresh cartridge in alignment with and behind a cartridge holder following the foremost cartridge holder, said loading member having a portion thereof arranged to engage such fresh cartridge to move it forwardly into assembly in said aligned cartridge holder concurrently as the foremost cartridge holder is moved forwardly by said loading member, a belt carrier movably mounted on the machine and adapted to successively position the cartridge receiving pockets of an ammunition belt in front of the foremost cartridge holder and in alignment with the path of said loading member, and means for operating said belt carrier in response to reciprocal movement of said loading member whereby each reciprocation of said loading member inserts said foremost cartridge holder in the ammunition belt and assembles a fresh cartridge in a following cartridge holder.

2. The combination defined in claim 1 plus an ejecting plunger connected to said loading member and arranged to project into said feed chute during each cycle of said loading member, said ejecting plunger being adapted to be insertable in a cartridge holder and arranged to enter into a cartridge holder at a position in said row behind the cartridge holder aligned with said fresh cartridge positioning means, thereby ejecting any fired cartridge from such cartridge holder.

3. A machine for assembling subcaliber ammunition comprising a reciprocable loading member, a feed chute adapted to receive a row of hollow cartridge holders, said feed chute having a discharging end disposed adjacent the path of said loading member whereby the foremost cartridge holder in said chute is positioned in the path of forward movement of said loading member, means for successively positioning a fresh cartridge in alignment with and behind a cartridge holder following the foremost cartridge holder, said loading member having a portion thereof arranged to engage such fresh cartridge to move it forwardly into assembly in said aligned cartridge holder concurrently as the foremost cartridge holder is moved forwardly by said loading member, an ejecting plunger connected to said loading member and arranged to project into said feed chute during each cycle of said loading member, said ejecting plunger being adapted to be insertable in a cartridge holder and arranged to enter into a cartridge holder at a position in the row behind the cartridge holder aligned with said fresh cartridge positioning means, whereby each cycle of movement of said loading member ejects any fired cartridge from one cartridge holder in the stack, loads a fresh cartridge into a preceding cartridge holder, and moves the foremost loaded cartridge holder out of said stack.

4. The combination defined in claim 3 plus a latch positioned adjacent the path of said ejecting plunger, said latch being constructed and ar-

ranged to engage the rim of a fired cartridge ejected by said ejecting plunger to prevent return movement of such cartridge.

5. A subcaliber ammunition assembling machine comprising a base, an operating member slidably mounted on said base for reciprocal movement including a forward loading stroke and a rearward return stroke, a generally vertical feed chute mounted on said base, said feed chute being adapted to support a stack of cartridge holders, said feed chute having a discharge opening adjacent the path of said operating member whereby the bottom cartridge holder of said stack is disposed adjacent the path of said operating member, said operating member having a first portion thereof engageable with such bottom cartridge holder on the forward loading stroke of said operating member to move the bottom cartridge holder out of said stack, and an ammunition tube mounted on said base in generally vertical relation and adapted to support a row of fresh cartridges, said tube having a discharge opening disposed rearwardly of said feed chute, overlying the path of said operating member and in alignment with a cartridge holder in said feed chute located above the bottom cartridge holder, said operating member having a second portion thereof arranged to engage the bottom cartridge in said tube on the forward loading stroke of said operating member to move such cartridge into the said aligned cartridge holder concurrently as the bottom cartridge holder is moved out of said stack.

6. The combination defined in claim 5 plus a spring member normally disposed relative to said ammunition tube to prevent the bottom fresh cartridge of the row from entering said tube discharge opening, and means on said operating member for moving said spring member out of said tube discharge opening once in each cycle of said operating member.

7. A subcaliber ammunition assembling machine comprising a base, an operating member slidably mounted on said base for reciprocal movement including a forward loading stroke and a rearward return stroke, a generally vertical feed chute mounted on said base, said feed chute being adapted to support a stack of cartridge holders, said feed chute having a discharge opening adjacent the path of said operating member whereby the bottom cartridge holder of said stack is disposed adjacent the path of said operating member, said operating member having a first portion thereof engageable with such bottom cartridge holder on the forward loading stroke of said operating member to move the bottom cartridge holder out of said stack, an ammunition tube mounted on said base in generally vertical relation and adapted to support a row of fresh cartridges, said tube having a discharge opening disposed rearwardly of said feed chute, overlying the path of said operating member, and in alignment with a cartridge holder in said feed chute located above the bottom cartridge holder, said operating member having a second portion thereof arranged to engage the bottom cartridge in said tube on the forward loading stroke of said operating member to move such cartridge into the said aligned cartridge holder concurrently as the bottom cartridge holder is moved out of said stack, and an unloading projection on said operating member arranged to pass during the rearward stroke of said operating member through a cartridge holder in the stack thereof at a higher level than

said second portion of said operating member, thereby ejecting any discharged cartridge out of the cartridge holder.

8. The combination defined in claim 7 plus a latch positioned adjacent the path of said unloading projection, said latch being constructed and arranged to engage the rim of a discharged cartridge ejected by said unloading projection to prevent return movement of such cartridge.

9. The combination defined in claim 8 plus a spring member normally disposed relative to said ammunition tube to prevent the bottom fresh cartridge of the row from entering said tube discharge opening, and means on said operating member for moving said spring member out of said tube discharge opening once in each cycle of said operating member.

10. The combination defined in claim 7 plus a spring member normally disposed relative to said ammunition tube to prevent the bottom fresh cartridge of the row from entering said tube discharge opening, and means on said operating member for moving said spring member out of said tube discharge opening once in each cycle of said operating member.

11. A belt loading machine comprising a base, an operating member slidably mounted on said base for reciprocal movement including a forward loading stroke and a rearward return stroke, a generally vertical feed chute mounted on said base, said feed chute being adapted to support a stack of cartridge holders, said feed chute having a discharge opening adjacent the path of said operating member whereby the bottom cartridge holder of said stack is disposed adjacent the path of said operating member, a belt carrier movably mounted on the machine and adapted to successively position the cartridge receiving pockets of an ammunition belt in front of the bottom cartridge holder and in alignment with the path of said operating member, said operating member having a first portion thereof engageable with such bottom cartridge holder on the forward loading stroke of said operating member to move the bottom cartridge holder into assembly in the ammunition belt, an ammunition tube mounted on said base in generally vertical relation and adapted to support a row of fresh cartridges, said tube having a discharge opening disposed rearwardly of said feed chute, overlying the path of said operating member, and in alignment with a cartridge holder in said feed chute located above said bottom cartridge holder, said operating member having a second portion thereof arranged to engage the bottom cartridge in said tube on the forward loading stroke of said operating member to move such cartridge into the said aligned cartridge holder, and means for operating said belt carrier in response to reciprocal movement of said operating member whereby each reciprocation of said operating member inserts said foremost cartridge holder in the ammunition belt and assembles a fresh cartridge in a following cartridge holder.

12. A belt loading machine comprising a base, an operating member slidably mounted on said base for reciprocal movement including a forward loading stroke and a rearward return stroke, a belt feed slide movably mounted on said base for reciprocable movement transverse to the path of said loading stroke, cam means for reciprocating said belt feed slide responsive to movement of said operating member, detent means on said belt feed slide adapted to engage an ammunition belt, whereby the cartridge recep-

tacles of such belt are successively positioned by said belt feed slide in alignment with the path of said operating member, a generally vertical feed chute mounted on said base, said feed chute being adapted to support a stack of cartridge holders, said feed chute having a discharge opening adjacent the path of said operating member whereby the bottom cartridge holder of said stack is disposed in the path of said operating member rearwardly of said belt feed slide, said operating member having a first portion thereof engageable with such bottom cartridge holder on the forward loading stroke of said operating member to move the bottom cartridge holder into assembly in said ammunition belt, an ammunition tube mounted on said base in generally vertical relation and adapted to support a row of fresh cartridges, said tube having a discharge opening disposed rearwardly of said feed chute, overlying the path of said operating member, and in alignment with a cartridge holder in said feed chute located above said bottom cartridge holder, said operating member having a second portion thereof arranged to engage the bottom cartridge in said tube on the forward loading stroke of said oper-

- ating member to move such cartridge into the said aligned cartridge holder, and an unloading projection on said operating member arranged to pass during the rearward return stroke of said operating member through a cartridge holder in the stack thereof at a higher level than said second portion of said operating member, thereby ejecting any discharged cartridge out of the cartridge holder.
10. 13. The combination defined in claim 12 plus a latch positioned adjacent the path of said unloading projection, said latch being constructed and arranged to engage the rim of a discharged cartridge ejected by said unloading projection to prevent return movement of such cartridge.
15. 14. The combination defined in claim 12 plus a spring member normally disposed relative to said ammunition tube to prevent the bottom fresh cartridge of the row from entering said tube discharge opening, and means on said operating member for moving said spring member out of said tube discharge opening once in each cycle of said operating member.

CHESTER E. HOSKINS.
